RADIO-FREQUENCY TRANSMISSION LINE

Wilbur Norman Christiansen, Melbourne, Victoria, Australia, assignor to Amalgamated Wireless (Australia) Limited, Sydney, New South Wales, Australia, a company of New South Wales

Application March 27, 1947, Serial No. 737,619
In Australia June 19, 1946

6 Claims. (Cl. 178—44)

1

The present invention relates to radio frequency transmission lines and more particularly to means for matching the characteristic impedance of a pair of multiple-wire lines to the characteristic impedance of a single multiple-wire line over a wide range of impedance values.

When open wire lines are employed for the transfer of high frequency energy from a transmitter to a remotely located antenna or from a receiving antenna to a remotely located receiver, it is desirable respectively to prevent radiation from and pick-up by the transmission line system.

In order to fulfill these requirements it has been the practice in the past to employ multiple-wire transmission lines. This type of line comprises a plurality of conductors connected electrically in parallel for conveying current in one direction, and another plurality of conductors for returning the current connected electrically in parallel, and so located that the loci of the electrical centres of both sets of conductors coincide. Since alternating currents are being dealt with, the directions referred to are instantaneous only. With such an arrangement there is no physical displacement between the opposite electrical charges and there is therefore neither radiation or collection of energy.

In transmission lines of this type, there are usually employed four parallel conductors arranged as at the corners of an imaginary square, and at each end of the line diagonally opposite conductors are connected together.

In certain applications involving the use of multiple lines of the 4-wire type it is necessary to effect a satisfactory impedance matching connection between a single 4-wire line and a pair of similar lines connected in parallel. In the past when this requirement has arisen, and matching at a plurality of frequencies is involved, the desired connection has been achieved by the use of a broad band impedance matching transformer.

This prior art method of coupling a single 4-wire line to a pair of 4-wire lines, has not been entirely satisfactory because of resistance losses introduced into the system by this form of coupling and its liability to damage by lightning.

The principal object of the present invention is to overcome the above-mentioned disadvantages and provide a transmission line arrangement for matching the characteristic impedance of a pair of four-wire lines without employing the conventional transformer.

A further object of the invention is to provide a transmission line arrangement whereby a pair of 4-wire lines may be conductively connected to

2

a single 4-wire line in impedance matching relationship.

- The above objects are achieved in accordance with the present invention preferably by the use of a multiple-wire transmission line section interposed between the ends of the pair of multiple-wire lines and the ends of the single multiple-wire line, said transmission line section comprising a plurality of conductors equal in number to the total number of conductors in said pair of multiple-wire lines and arranged about a common axis at equal radial distances therefrom. The foregoing arrangement is such that the conductors of said line section are disposed about the circumference of an imaginary circle having a diameter at one end of said transmission line section equal to the diagonal dimensions of each of said pair of multiple-wire lines, the individual conductors of which latter are alternately and sequentially connected to separate and alternate conductors of said transmission line section at said one end. The diameter of said imaginary circle at the other end of said transmission line section is equal to the diagonal dimensions of said single multiple-wire line whose individual conductors are separately and sequentially connected to pairs of adjacent conductors of said transmission line section, the alternate conductors of said line section being simultaneously and progressively varied in the same direction of angular movement about the common axis of the said transmission line section to cause a variation in the spacing between adjacent conductors at opposite ends thereof.
- For a more complete understanding of the invention and the manner in which it is to be carried out attention is now directed to the following description in connection with the accompanying drawing in which:
- Fig. 1 is a diagram illustrating the placement of the conductors of a transmission line according to the invention; and
- Fig. 2 is an illustration of a practical construction of a transmission line according to the invention.
- In the exemplary arrangement covered by the following description, the invention provides a matching system for connecting a pair of 4-wire balanced transmission lines to one 4-wire balanced transmission line. In its simplest form the invention involves running the two sets of 4-wire feeders along a common axis thus forming an 8-wire line. The impedance of this 8-wire line may be readily varied by rotating one set of 4-wires with respect to the other set.

At the point in the system where the conductors of the two 4-wire lines coalesce the conductors 2, 4, 6, 8 of one line and the conductors 3, 5, 7, 9 of the other line, are alternately arranged and symmetrically disposed in any convenient manner about a common axis to form an 8-wire line of octagonal cross section as shown in Fig. 1 of the drawing. Although in order to clarify the explanation of the invention, the conductors comprising the separate 4-wire lines have been shown in the drawing of different cross section, it is to be understood that all of the conductors are preferably of the same proportion and that the physical dimensions of both of the 4-wire lines are the same. In these circumstances when the conductors of the two lines are brought together to form the 8-wire line of octagonal cross section as described above they are located at each of the vertices of the octagon and are thus symmetrically disposed about the circumference of a circle having diameter equal to the diagonal dimensions of each of the 4-wire lines and whose axis coincides with the axis of the composite line.

Two conductors in each 4-wire line are shaded in the drawing for the purposes of identification. By rotating one set of conductors 2, 4, 6, 8 with respect of the other set 3, 5, 7, 9 so that the angle formed by the intersection of two lines joining the diametrically opposite conductors of each 4-wire line is caused to vary, the wave impedance along the composite line can be caused to change in any desired manner, e.g. exponentially over a range of impedances greater than two to one. It has been found that there results a very simple expression for the characteristic impedance of such a line, this being

$$Z_0 = 69 \log_{10} \frac{D}{d} \cot \theta$$

where

D is the diameter of the circle containing all the wires,

d is the diameter of the wire,

θ is the angle of rotation shown in the drawing.

If at the end of the 8-wire line to which the pair of 4-wire lines are connected the conductors are disposed in the physical arrangement shown in the accompanying drawing the angle θ will be 45 degrees and the characteristic impedance Z_0 at this end of the 8-wire line will be equal to half the value of the characteristic impedance of each of the 4-wire lines. This facilitates an impedance matching coupling between the pair of 4-wire lines and the composite 8-wire line by direct connections.

The characteristic impedance at the other end of the 8-wire line will depend upon the physical relationship of the conductors and the value of the angle θ at that end.

By simply rotating one set of 4-wires with respect to the other set the angle θ is caused to vary and it is possible to adjust the characteristic impedance of the line at that end to any predetermined value over a wide impedance range.

Rotation of 1 set of 4-wires with respect to the other set over the length of line separating the ends to cause an increase or decrease in the value of the angle θ will cause a decrease or increase respectively in the value of the characteristic impedance of the resultant line.

In the present example by rotating the conductors 2, 4, 6, 8 in a clockwise direction about the 75 cent conductors.

axis of the line so as to decrease the value of the angle θ the characteristic impedance of the 8-wire line may be increased to a value such as will permit direct connection to a single 4-wire line in impedance matching relationship. It is possible; also, to vary the angle θ and the ratio D/d simultaneously, and this is often useful.

It is well known that the length required for an exponential transmission line is determined by (i) the magnitude of the impedance transformation ratio, (ii) the lowest frequency of the current required to pass along the line and (iii) the maximum deviation from the correct transformation ratio that can be tolerated. The higher the transformation ratio or the lower the maximum frequency or the smaller the allowable deviation, the longer must be the exponential line.

The number of supports required for such an exponential line will be determined often by the requirement of mechanical stability. Apart from this, however, there is a minimum number of supports that can be used if the exponential form of the line is to be preserved. It is found possible

25 with the 8-wire line, described here, to achieve a line that in a two-to-one range of impedance departs by less than one per cent from the true exponential form, when the line is supported only at the ends and one other point. As an example

30 of this consider a line designed for an impedance transformation from 131 ohms to 262 ohms. In one design for such a line, illustrated in Fig. 2 of the drawing, supports are provided at the ends and the centre. Over one half of the line the angle θ only is varied, while over the other half θ and D are simultaneously varied. Referring to Fig. 2, there is shown by way of example only a practical arrangement of a transmission line according to the invention, the constructional

35 details of the arrangement not being a part of the invention. Equally spaced supports 21, 22 and 23 are provided with apertures 31, 32 and 33, respectively. Apertures 32 and 33 are of the same diameter and smaller than aperture 31. Cross-

40 shaped members 41, 42 and 43 having feed through insulators 27 located near the ends are arranged on one side respectively of supports 21, 22 and 23 and members 51, 52 and 53 similarly fashioned are arranged on the other side respectively, the rotatable complementary members being held in place after adjustment by clamp action brought about by bolts 54 of like fasteners. Insulators 27 are placed so that conductors 2-9 pass through apertures 31, 32 and 33. The 45 dimensions of the line at the three supporting points are respectively:

- (1) $\theta=67.5^\circ, D/d=190$
- (2) $\theta=22^\circ, D/d=190$
- (3) $\theta=6.2^\circ, D/d=660$

50 What I claim is:

1. Improvements in radio frequency transmission lines of the multiple-wire type, residing in an arrangement for varying the characteristic impedance of a parallel connected pair of such lines over a wide range of impedance values, said arrangement consisting in disposing the individual conductors of said lines in parallel relationship with each other, and alternately and symmetrically about a common axis, at equal distances therefrom, the arrangement being such as to provide for simultaneous rotation of the conductors of either of said lines about said common axis so as to vary the spacing between adjacent conductors.

2. Improvements in radio frequency transmission lines of the multiple-wire type, residing in an arrangement for varying the characteristic impedance of a pair of parallel connected 4-wire transmission lines over a wide range of impedance values, said arrangement consisting in disposing the individual conductors of said 4-wire lines in parallel relationship with each other, and alternately and symmetrically about a common axis, at equal distances therefrom, the arrangement being such as to provide for simultaneous rotation of the conductors of either of said lines about said common axis so as to vary the spacing between adjacent conductors.

3. Improvements in radio frequency transmission lines of the multiple-wire type, residing in an arrangement whereby a pair of parallel connected 4-wire lines may be directly connected to a single 4-wire transmission line in impedance matching relationship, said arrangement consisting in disposing the individual conductors of said 4-wire lines in parallel relationship with each other, and alternately and symmetrically about a common axis, at equal distances therefrom, the arrangement being such as to provide for simultaneous rotation of the conductors of either of said lines about said common axis so as to vary the spacing between adjacent conductors.

4. Improvements in radio frequency transmission lines of the multiple-wire type, characterized by a multi-wire transmission line section interposed between the ends of a pair of multiple-wire lines and the ends of a single multiple-wire line the impedance of which is to be matched with said pair, said transmission line section comprising a plurality of conductors equal in number to the total number of conductors in said pair, and arranged alternately and symmetrically about a common longitudinal axis, the arrangement being adapted for simultaneously rotating said alternate conductors about said common axis to vary the spacing between adjacent conductors.

5. Improvements in radio frequency transmission lines of the multiple-wire type, residing in an arrangement for varying the characteristic

impedance of a pair of parallel connected four-wire transmission lines over a wide range of impedance values, said arrangement consisting in disposing the individual conductors of said 4-wire lines in parallel relationship with each other, and alternately and symmetrically about a common axis, at equal distances therefrom to constitute an eight-wire line, the arrangement being such as to provide for simultaneous rotation of the conductors of either of said lines about said common axis so as to vary the spacing between adjacent conductors permitting of impedance matching coupling between said eight-wire line and said pair of four-wire lines by direct connection.

6. Improvements in radio frequency transmission lines of the multiple-wire type, residing in an arrangement for varying the characteristic impedance of a pair of parallel connected four-wire transmission lines over a wide range of impedance values, said arrangement consisting in disposing the individual conductors of said 4-wire lines in parallel relationship with each other, and alternately and symmetrically about a common axis, at equal distance therefrom, the arrangement being such as to provide for simultaneous rotation of the conductors of either of said lines about said common axis so as to vary the spacing between adjacent conductors, said arrangement of said lines being supported only at the ends thereof and at one other point.
